Primary Examiner — Katherine Glennon(74) *Attorney, Agent, or Firm* — Fross, Zelnick, Lehrman & Zissu, P.C.; Charles T. J. Weigell, Esq.**CLAIM**

The ornamental design for a watch as shown and described.

DESCRIPTION

FIG. 1 is a front perspective view of a watch showing my new design;

FIG. 2 is a front view thereof;

FIG. 3 is a back view thereof;

FIG. 4 is a top view thereof;

FIG. 5 is a bottom view thereof;

FIG. 6 is a left side view thereof; and,

FIG. 7 is a right side view thereof.

The broken lines in the figures represent portions of the watch that form no part of the claimed design.
